UNITED STATES PATENT OFFICE.

FRANKLIN G. NEAL, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

OIL-BURNING FURNACE.

Application filed June 8, 1924. Serial No. 717,846.

This invention relates to improved means for controlling the operation of a power operated oil burning furnace, particularly for household use or where it is not convenient to have an operator's attention to adjust the furnace accessories under desired conditions.

It is old to operate the burner in various ways by the power from an electric motor, which either supplies both air and oil or only one of the combustible materials to the flame desired. Such an arrangement is shown in the Welch Patent No. 1,183,786, dated May 16, 1916. It may frequently happen that the current to the motor will fail at a time when the furnace should be in full operation. It is not unusual for even a well managed city electric service to go out of commission entirely for various reasons.

20 An appreciation of these conditions, with regard to household furnaces presents the problem of this invention.

According to the invention, I provide means to automatically shift the burden of 25 operating the furnace from the usual source of power to an independent source of power when the usual source fails for any reason. I have carried his means, in one of its forms, to the point of automatically shifting from 30 the usual to the emergency source of power and back again, as the usual source of power is rendered first unavailable and then available.

It is customary to prevent further operation 35 of the power means whenever the furnace goes out and the burner floods with oil, according to the overflow bucket switch operated means as in said Welch patent. I avail myself of the movement of said bucket 40 switch operated means to prevent the operation of both the usual and emergency power means in my device under the same conditions.

It is also customary to control the feed of 45 the combustible units to an oil burning furnace according to a thermostatic connection, preferably with the place to be heated and the furnace, so that the furnace will generate more or less heat accordingly as it is 50 needed at the point of use just as in coal burning furnaces. Because of this fact, and as a convenient means of fitting both sources of power, which may be used alternatively, according to my invention, to the operating

conditions of an oil furnace embodying the 55 invention, I have indicated a thermostatic control over both sources of power. But this thermostatic control does not determine which source of power is used, but only controls whatever source is connected for operation according to conditions independently determined. The thermostat control might be entirely omitted from the showing of this case, but I have shown it to make the adaptation of my furnace, particularly 60 to household use, more complete.

With the foregoing in mind, I will illustrate an embodiment of my invention more or less diagrammatically but entirely sufficient for one skilled in the art to adapt it 70 in other specific forms for convenient use, according to the particular furnace and burner constructions available.

In the drawings:

Fig. 1 is a sectional elevational view showing a power operated oil burning furnace embodying my invention; and

Fig. 2 is a fragmentary view, taken similarly to Fig. 1, showing a modification in the emergency control mechanism.

Referring to these drawings, there is shown in Fig. 1 an illustrative example of one of many suitable oil burning furnaces and power operated oil burners therefor, with which my invention may be used. The 85 furnace includes a fire box A, having a suitable floor B of refractory material, which floor is provided with a central opening C to admit air from the ash pit D, therebelow.

The oil burner includes a centrifugal 90 atomizer and distributor 10, to which oil and preferably air, is supplied. The atomizer is fixed to the upper end of a vertically disposed shaft 11, mounted in bearings 12, carried by a frame 13. As shown, oil is 95 supplied to the atomizer from a reservoir 14 by way of an axial passage 15 in shaft 11, the admission of oil thereto being regulable by a needle valve 16, cooperating with the opening in the lower end of the shaft. The 100 passage 15 is tapering and diverges upwardly so that rotation of the shaft causes the oil to be lifted from the reservoir to the atomizer by centrifugal action. The oil, as it is lifted, is spread out into a film on the 105 walls of the passage 15, and this film becomes thinner and thinner as it passes upwardly. When the oil emerges into the

atomizer it is met by a flow of air induced through openings 17 by fan blades 18 and is discharged through a peripheral outlet 19 in the condition of a mist or fog and mingled 5 with the main stream of air passing upwardly through opening C.

The shaft is arranged to be driven from a normal source of power, which may, for example, be an electric motor 20. As shown, 10 the motor is directly connected to a horizontal shaft 21 which by gearing, indicated in part at 22, drives shaft 11. The motor, casing 13, and reservoir 14, are all mounted in a common bed plate E, which is suitably 15 supported from the floor by means not shown. In addition to the normal source of power, an independent source is provided for emergency use. As shown, the independent source of power consists of a water motor 23, the rotor of which is fixed to shaft 21. Obviously, other sources of power may be substituted for the motors 20 and 23 and I have selected the illustrated motors as examples and as likely sources available and 20 suitable for household use.

The electric motor 20 is provided with controlling means by which it is started and stopped when required in normal operation. Usually, such means are responsive to the 30 temperature of the room to be heated, and I have illustrated conventionally at 24 a room thermostat adapted, when the temperature in the room falls below a predetermined point to engage a contact 25 and close an electric circuit through a battery 26 and solenoid 27, whereby the latter is energized and functions to move a disc 28 against a pair of contacts 29. The latter are included in series in one of the line wires 30 and 31 leading 35 from the supply of electricity to motor 20.

In addition to the normal control for motor 20, which has just been described, there is an emergency control, whereby the burner. 40 will be stopped, and with it the supply of oil to the furnace, whenever the dangerous condition arises. The particular dangerous condition which, as an illustrative example, I have chosen to guard against is the flooding 45 of the furnace with oil. Whenever combustion of the oil ceases for any reason, the unconsumed oil thrown out from the atomizer 10 is collected by drain pipes 32, and delivered into a bucket 33 and as in the 50 Welch patent, above identified, an accumulation of such oil causes an emergency switch to be opened for the purpose of stopping motor 20. The emergency switch is designated 55 34 and is included in series with one of the wires 30 or 31 leading to motor 20. As best shown in Fig. 2, the switch 34 includes a plunger 35 carrying a contact plate 36, and this plunger is normally held by a spring 37 in position to connect two contacts 38. The 60 plunger is pivotally connected to a lever 39

carrying bucket 33 and when the weight of oil in the latter overpowers spring 37, the contact plate 36 will be drawn downwardly away from contacts 38 to open the circuit to motor 20.

The auxiliary source of power is brought into play to operate the burner on failure of the normal source of power. In the illustrated form of the invention all that is necessary for the purpose of starting the motor 70 23 is to admit water thereto through its supply pipe 40. In this pipe, I provide a main controlling valve 41, which automatically opens when the supply of electricity fails. The valve tends to open under the influence of a spring 42, but is normally held to its seat by a lever 43 which in turn is held in place by a latch 44. Connected to latch 44 is the plunger of a solenoid 45, and a spring 46 tends to lift the latch and release lever 43 and allow valve 40 to open. To prevent this action the solenoid is included 80 shunt with the line wires 30 and 31 so that so long as a supply of electricity is available the solenoid is energized and valve 41 held closed, even though motor 20 be started and stopped by the thermostat control any number of times. That is, the opening of the motor circuit by the thermostat does not open the circuit to solenoid 45. However, 85 when the supply of electricity fails, the solenoid is deenergized and the valve 41 opened.

The lever 43, when released to allow opening of valve 41, engages and connects two contacts 47, which are included in an electric circuit through a battery 48 and an alarm bell 49, whereby an alarm may be sounded to give notice of the failure of the electricity and the necessity of eventually resetting the operating mechanism for valve 40.

The mechanism for changing from one form of power to another need not necessarily be of the form described, nor need it be of such form as to require resetting. Wherever it is desired not only to change from the normal source, but also to change back again, a mechanism, such as shown in Fig. 2, may be used. Here the valve 41 is also of the self opening type but is held closed by a solenoid 50 against the action of a spring 51. Solenoid 50 is connected in the same manner as solenoid 45, so that if the supply of electricity fails, it will be deenergized to permit automatic opening of valve 41, but whenever the supply of electricity is again available, solenoid 50 is energized and acts to close valve 41.

It should be noted that the mechanism for changing from the normal to the auxiliary source of power is likewise effective upon any failure of the motor 20, which will blow the fuses in the line wires and thereby cut off the supply of electricity to solenoid 45.

The motor 23 may be, and preferably is,

controlled by the same normal controlling means employed for motor 20 so that no interruption of the automatic operation of the burner occurs. To this end, I provide a 5 second valve 52, in the supply pipe 40, which valve is normally closed by a spring 53 but may be opened by a solenoid 54, when the latter is energized. For energizing the solenoid, I provide a battery 55 and an electrical 10 circuit including both, which circuit can be closed by a second disc 56, which is mounted on the plunger of the thermostatically controlled solenoid 27. Thus, when the thermostat closes the circuit to motor 20, it also 15 closes the battery circuit to solenoid 54, but the opening of valve 52 is not effective to start the water motor 23 unless the valve 41 is open. Also should the supply to motor 23 fail at a time when it was not running, be- 20 cause operation of the burner was not needed, then although the valve 41 would be opened as described to render motor 23 effective to operate the burner, the latter would not be actually operated until needed and 25 not until the thermostat 24 engages the contact 25.

The emergency device for stopping motor 20 is also arranged to stop the water motor 23 under the same conditions. As shown in 30 Fig. 2, a third valve 58 is provided in supply pipe 40 and this valve is normally open. A lever 59, pivoted to the valve casing, is connected by a link 60 to the lever 39, which carries bucket 33, whereby, on an accumulation 35 of oil in the bucket, valve 58 will be automatically closed so that neither source of power is thereafter effective to operate the burner until the trouble is remedied.

The normal operation of the oil burner is 40 substantially the same as usual. The motor 20 is started and stopped automatically by the thermostatic control according to heat requirements and may be stopped automatically by the emergency device on the occurrence 45 of a dangerous condition in the furnace. On failure of the supply for motor 20, or on any failure of the motor 20 which will interrupt the supply thereto, the auxiliary source of power is automatically rendered effective to operate the burner and will 50 operate the same, whenever the automatic thermostat control determines the necessity for operation, and according to the dictates of such control. Should, however, the emergency stop device have been operated, the 55

water motor cannot be started to continue a dangerous condition. The means whereby the change is made from the normal to the auxiliary source of power is likewise effective to change back from the auxiliary to the normal source whenever the latter is again capable of bearing the burden of operating the furnace.

The invention has been disclosed, in an embodiment at present preferred, for illustrative purposes, but the scope of the invention is defined by the appended claims rather than by the foregoing description.

What I claim is:

1. The combination with a power operated 70 oil burner, of a normal and an independent driving means therefor, controlling means for both said driving means but normally effective only to start and stop said normal driving means, and means operable on failure of said normal driving means to render the independent driving means effective to be controlled by said controlling means whereby it is effective to operate the burner.

2. The combination with a power operated 80 oil burner, of a normal and an independent driving means therefor, controlling means for both said driving means but normally effective only to start and stop said normal driving means, and means operable on failure of said normal driving means to render the independent driving means effective to be controlled by said controlling means, whereby it is effective to operate the burner, and operable when the normal driving means is again capable of operating the burner to render the independent driving means ineffective to operate the burner.

3. The combination with a power operated 90 oil burner, of a normal and independent driving means therefor, controlling means for both said driving means but normally effective only to start and stop said normal driving means, means operable on failure of said normal driving means to render the independent driving means effective to be controlled by said controlling means, whereby it is effective to operate the burner, and means operable on flooding of the burner to render both said driving means ineffective 100 to operate the burner.

In testimony whereof I have affixed my signature.

FRANKLIN G. NEAL.
